UNITED STATES PATENT OFFICE.

JACOB W. H. GLASS, OF READING, PENNSYLVANIA.

FOLDING IRONING TABLE.

1,408,880.

Specification of Letters Patent.

Patented Mar. 7, 1922.

Application filed September 10, 1920. Serial No. 409,300.

To all whom it may concern:

Be it known that I, JACOB W. H. GLASS, a citizen of the United States, and a resident of Reading, in the county of Berks and State 5 of Pennsylvania, have invented an Improvement in Folding Ironing Tables, of which the following is a specification.

My invention relates to folding ironing tables, and it has for one of its objects to 10 provide an ironing table structure which may be collapsed or folded without disconnecting any of the parts thereof.

A further object of my invention is to provide an improvement in the means of adjusting the supporting legs with relation to 15 each other so as to effect the raising or lowering of the table as may be desired.

Other objects and advantages of my invention will be set forth in the detailed description thereof which follows and will be 20 apparent from such description.

In order that my invention may be readily understood and its practical advantages 25 fully appreciated, reference may be had to the accompanying drawings in which I have illustrated certain forms of convenient embodiments thereof. However, it will be understood that my invention is susceptible of embodiment within the scope of the claims 30 in other forms than are illustrated in the drawings.

In the drawings,—

Fig. 1 is a perspective view of an ironing table showing a preferred form of embodiment of my invention;

Fig. 2 is a central vertical section taken along the line 2—2 of Fig. 1;

Fig. 3 is a horizontal sectional view taken along the line 3—3 of Fig. 2;

Fig. 4 is a perspective view showing the table in collapsed condition, the said view showing the under side or leg structure of the table;

Fig. 5 is a perspective view showing a 45 modified construction of table embodying my invention.

Referring to the drawings,—1 designates a couple of supporting legs pivotally connected by a connecting rod or bar 2 to a 50 couple of legs 3. The lower end of the legs of each couple of legs 1 and 3 are connected by cross rods or bars 4 and 5. Each couple of legs 1 and 3 may be regarded as constituting a leg unit. The upper ends of the 55 legs 1 are pivotally connected by pivots 6

to the opposite ends of a bar 7 which is secured by fastening devices, such as screws 8, to the under side of the table top or board 9. The upper ends of the legs 3 are connected by means of a cross bar 15. To this cross 60 bar links are pivotally connected, each link comprising an outer link section 16 provided with a longitudinal slot 17 in its inner end portion through which the connecting rod or bar 15 extends. Each link is also provided 65 with a relatively short link section 18 having an opening 19 therethrough, through which the connecting rod or bar 15 extends, the said opening 19 permitting pivotal movement between the said link section 18 and 70 the said connecting cross rod 15. Each of the short link sections 18 is provided with a longitudinal slot 20 through which a headed screw-thread bolt 21 extends, the said bolt extending through the slot 20 and through 75 an opening 22 in each of the links 16 as best shown in Fig. 3 of the drawings. The openings 22 through the links 16 are situated a distance outwardly from the outer ends of the longitudinal slots or openings 17. The 80 bolts 21 are provided with wing nuts 25 which are adapted to be loosened and tightened for the purpose of permitting relative adjustment between the link sections 16 and 18. It will be observed by reference to Figs. 85 1, 2 and 3 of the drawings, that the connecting rod 15 may be positioned either at the inner or outer ends of the slots 17 and obviously at any intermediate point or position therein. Also it will be apparent from an 90 inspection of these figures that when the links are adjusted so as to position the rod 15 at the outer ends of the slots 17 as shown in Fig. 3 of the drawings, the relatively short link sections 18 are moved outwardly toward 95 the block or bar 26 to the outer ends of which the outer ends of the link sections 16 are pivotally connected by means of pivots 27. The cross bar or block 26 is secured by fastening means, such as a screw or screws 100 28, to the underneath side of the table top or board 9. The bar 26 is situated at a point intermediate the opposite ends of the table top or board as shown.

It will be apparent from an inspection of 105 the drawings that when the links 16 and 18 are adjusted so as to occupy the positions relative to each other as shown in Fig. 1, the legs 1 and 3 are spread apart to their fullest extent and the table top or board occupies 110

its lowermost position above the floor or other support. On the other hand, when the link sections 16 and 18 are adjusted with respect to each other so that they occupy the relative positions shown in Figs. 2 and 3 of the drawings, the leg couples 1 and 3 have been moved so as to bring their upper and lower ends in closer relation in respect to each other so that the height of the table top or board is increased to the highest point to which it may be adjusted. If, by means of the bolts 21 and binding nuts 25, the links are adjusted so as to position the bolts 21 at intermediate points within the slots 20 in the short link sections 18 and the connecting rod 15 in different corresponding positions, within the slots 17 in the link sections 16, the table will be adjusted to heights intermediate the heights shown in Figs. 1 and 2.

The legs 3 are further connected together and braced by means of the cross strips 30.

In order to collapse the table structure and fold the same with the parts in the positions indicated in Fig. 4 of the drawings, the left hand end of the table or board, having reference to Figs. 1 and 2 of the drawings, is raised and simultaneously the upper ends of the legs 3 are turned or moved toward the right so as to carry the inner ends of the links comprising the sections 16 and 18 relatively downwardly and toward the right, again having reference to Figs. 1 and 2 of the drawings, so that ultimately the said links and both pairs of legs may be folded flat against the under side of the table with the upper ends of the legs 3 and with the inner ends of the links comprising the sections 16 and 18 occupying positions adjacent to the inner side of the bar 7, as clearly shown in Fig. 4 of the drawings.

In Fig. 5 I have shown a modification of the structure in which the parts 1, 2, 3, 4, 5, 6, 7, 8, 9, 15, 26, 27, 28 and 30 are identical with the parts correspondingly numbered in the previous figures of the drawings.

Each of the links 35, however, consist of single sections or elements which are not adjustable. The inner ends of these links 35 are connected to the connecting cross rod 15 at the upper ends of the legs 3, while the outer ends thereof are connected to the pivots 27. The construction as shown in this figure may be collapsed just as is shown in Fig. 4, but by reason of the fact that the links 35 are fixed in length, the table top or board cannot be adjusted to different heights with respect to the floor or other support on which the ironing table may be supported.

Having thus described my invention, what I claim, and desire to secure by Letters Patent, is:

1. In a folding ironing table, the combination of leg supports, said leg supports adapt-

ed to be crossed when in supporting position, the upper end of one of said leg supports being pivotally connected to the table top, a link structure pivotally connected at one end to an intermediate portion of the table top, and means for adjustably connecting and positively engaging the upper end of the other of said leg supports with the outer swinging end portion of said link structure at desired points of the latter.

2. In a folding ironing table, the combination of two couples of legs, said couples being pivotally connected at a point intermediate their ends, the upper end of one couple of said legs being connected at a fixed point to the table top, links pivoted to the upper ends of the legs of the other couple and pivotally connected to an intermediate portion of the said table top, a distance from the point of connection of the upper ends of the legs of the other couple to said top, means for adjusting the pivotal connections along said links to thereby effect raising or lowering of the said table.

3. In a folding ironing table, the combination of crossed leg units pivotally connected at their point of crossing, stationary pivots for connecting the upper end of one of said units to the top of said table, means for swingingly connecting an upper end of the other leg unit to the said table, said means comprising a link consisting of two link sections longitudinally adjustable with respect to each other, and means for holding the said sections in adjusted position.

4. In a folding ironing table, the combination of two couples of crossed leg supports, the said couples being pivotally connected at their point of crossing, stationary pivots for connecting the upper ends of the legs of one of said couples to the said table, links swingingly connecting the upper ends of the legs of the other couple to the said table, each link consisting of two sections, one being longer than the other, the shorter section being provided with a longitudinally extending slot, and means for adjustably connecting the said sections together, the said means being carried by the longer section and extending through the slot in the shorter section.

5. In a folding ironing table, the combination of two couples of crossed supporting legs, stationary pivots for connecting the upper ends of the legs of one couple to the table top, a cross rod connecting the upper ends of the legs of the other couple, links for connecting the upper ends of the legs of the last mentioned couple to an intermediate portion of the table top, each link comprising two sections, one section being longer than the other, the longer section being provided with a longitudinally extending slot in its inner end portion through which the

said connecting rod extends, and the said shorter section being provided with a hole at its inner end through which the said connecting rod extends and also being provided 5 with a longitudinally extending slot, means for adjustably connecting the sections of each link together, the said means being car-

ried by the longer section and extending through the slot in the shorter section, substantially as described.

In testimony that I claim the foregoing as my invention, I have hereunto set my hand this 13th day of August, 1920.

JACOB W. H. GLASS.
